CLAIM

The ornamental design for a packaging insert, as shown and described.

DESCRIPTION

FIG. 1 is a top perspective view of the packaging insert shown inside an open box.

FIG. 2 is a top perspective view of the packaging insert.

FIG. 3 is front view thereof.

FIG. 4 is a back view thereof.

FIG. 5 is left side view thereof.

FIG. 6 is right side view thereof.

FIG. 7 is top view thereof.

FIG. 8 is bottom view thereof; and,

FIG. 9 is a bottom perspective view thereof.

In FIG. 1, the broken lines depict both a box and portions of the packaging insert that form no part of the claimed design; the broken lines in FIGS. 2-9 show portions of the packaging insert that form no part thereof.

1 Claim, 6 Drawing Sheets
